US00D689828S

(12) **United States Design Patent**
Pierson

(10) **Patent No.:** **US D689,828 S**
(45) **Date of Patent:** **** Sep. 17, 2013**

(54) **DOORBELL BUTTON**

(75) Inventor: **Theodore F. Pierson**, Seattle, WA (US)

(73) Assignee: **Theodore Pierson**, Seattle, WA (US)

(**) Term: **14 Years**

(21) Appl. No.: **29/372,150**

(22) Filed: **Oct. 25, 2010**

(51) LOC (9) Cl. **13-03**

(52) U.S. Cl.

USPC **D13/174**

(58) **Field of Classification Search**

USPC D13/171, 174; D8/310; D10/108,
D10/118, 121; 200/5 A, 47, 510, 513, 520,
200/530, 341
